KNITTING MACHINE

Frank R. Page, Laconia, N. H., assignor to Scott & Williams, Incorporated, Laconia, N. H., a corporation of Massachusetts

Application October 20, 1943; Serial No. 506,989

8 Claims. (Cl. 66—48.)

This invention relates to improved means for effecting the picking of needles in the formation of fashioned portions of knitted wear as, for example, the heel and toe pockets of stockings.

In knitting machines having independent needles, fashioning is accomplished by picking needles out of action, as in the narrowing operation of forming a heel or toe, and thereafter picking the inactive needles into operative position, as in the widening of heels and toes.

Consider, for example, a knitting machine having a rotary needle cylinder. The picks when idle are stationary, but when engaged by a leading needle of a differentiated series, will be moved laterally, at the same time being guided to move axially and engage the butt of, and thereby move longitudinally, the needle effecting the lateral movement and sometimes one or more adjacent needles. The picking of a plurality of needles is the usual procedure effected by the widening pick in a widening operation, whereas, for narrowing and also in the widening operation a single needle is generally picked by the narrowing picks at each operation though under some circumstances there may be multiple needle picking of needles out of action. The butts which are acted on by the picks are not always carried by needles directly but may be carried by jacks or sliders as, for example, in double cylinder machines. It will be understood that in stationary cylinder machines the same relative picking movements result, though in such case the picks rotate, having differential movements imparted to them upon their engagement with butts.

Picking action of the type just indicated is conventional, and is ordinarily attained with no difficulties. Troubles, however, have been experienced in group needle picking in fine gauge knitting, particularly on fine gauge hosiery machines. The trouble is due in a large measure to the flexibility of the fine gauge needle butts and the walls of the needle cylinders between which the needles slide during knitting. Due to this flexibility and to close arrangement of needle butts, as well as to the fact that in multiple needle picking the picks necessarily have a substantial lateral extension, a pick is likely to have a movement relative to the needle cylinder of sufficient lateral extent to pick a needle beyond the group desired, whereby the prescribed picking sequence would be disturbed.

It is the broad object of the present invention to provide improved picking means whereby the difficulties just indicated are avoided and proper picking of only the desired needles is insured.

This general object, as well as other objects of the invention, particularly relating to details, will become apparent from the following description read in conjunction with the accompanying drawing, in which

Figure 1 is a view in side elevation of a widening pick assembly provided in accordance with the present invention, mounted in a bracket carried by the bed plate of a hosiery knitting machine;

Figure 2 is an elevation of the same viewed from the face adjacent the needle cylinder;

Figure 3 is an enlarged detail view showing the pick of Figures 1 and 2 and adjacent parts; and

Figure 4 is an elevation showing the end of a narrowing pick also embodying the principles of the invention.

Referring first to Figures 1, 2, and 3, there is illustrated therein a widening pick 2 having a shank 4 pivoted within a slot 8 in a shaft 10 by means of a pivot pin 6, the shaft 10 being mounted for rotation in a bracket 14 secured to the bed plate 16 of the knitting machine. A spring 12 urges the shaft 10 and the pick carried thereby in a counterclockwise direction as viewed in Figure 1. From one end of the shaft 10 there extends an arm 18 engageable by a spring-urged button 20 to move the pick 2 downwardly from the picking position illustrated in Figure 1 to render it inoperative at the proper times.

Cam plate 22 carried by the bracket 14 is provided with an inverted V-shaped opening having sides 24 and 26 within which opening the shank 4 of the pick normally rests under the action of the spring 12. This plate 22 has laterally extending lower edges 28 and 30 forming continuations of the sides 24 and 26 of the opening.

Pivoted to the bracket at 36 are arms 32 and 34 extending upwardly on opposite sides of the shank of the pick, these arms being urged toward each other by a spring 38 connected between them, and being guided by a plate 40 which positions them and also limits their movements.

To the extent so far described the pick assembly is conventional and is as illustrated, for example in Patent No. 1,841,205, dated January 12, 1932.

Conventionally, the inner butt-engaging end of the pick is provided with a central downwardly extending portion and laterally extending wings, the lower surfaces of which lie in a common plane. In accordance with the present invention, however, the wings shown at 42 and 44 have their lower edges sloping downwardly and

outwardly being in a sense undercut as indicated at 46.

Above the central position of the pick is a cover cam 48 having sloping edges 50 and 52 terminating in downwardly directed points which are slightly below the outermost ends of the wings 42 and 44.

The widening pick illustrated in Figures 1, 2, and 3 is designed to lower four needles in a single operation. As shown particularly in Figure 3, 10 the butt 54 of the first needle (or jack or slider) of a group riding at the inactive level has just engaged the pick 2. The butts in approaching the pick will have passed down the edge 52 of the cam 48 so that they are brought to a level to 15 pass below the right-hand end of the wing 44. At the time the butt 54 engages the pick, four butts will be beneath the right-hand wing. As the movement of the needle cylinder proceeds, the pick 2 will be moved toward the left as viewed 20 in Figure 3 so that its shank will ride down the cam edge 24 of the opening in the plate 22. As such downward movement of the pick takes place it will, due to the slope of the lower surface of 25 the wing 44, engage successively the butts of the fourth, third, and second needles before engaging the butt of the needle 54. As a result the static friction loads of the four needles are assumed successively and the kinetic friction load is assumed gradually. Since the load imposed to 30 effect downward movement of the pick is taken up by the leading needle butt 54 alone, it will be evident that this butt is much less loaded, as well as less suddenly loaded, than would be the case if all four butts were engaged simultaneously, so that a minimum deflection of the butt 54 toward the right relative to the other butts occurs at the time that descent of the fourth butt 55 begins. If thereafter, as the other butts are 35 successively encountered by the wing, the butt 54 does deflect still more, the result, nevertheless, cannot be that of permitting the pick to engage the fifth butt 56, inasmuch as the right-hand end of the wing 44 will have dropped below the 40 upper edge of this butt even before two butts are engaged. The result is that even if abnormal flexure of the butt 54 takes place relative to the cylinder, after loading of the pick by several butts occurs, so as to cause the end of the wing 44 to be engaged by the butt 56, that engagement will be merely on the side face of the butt 56 under relatively low pressure so as not to cause the butt to be lowered.

As the shank of the pick leaves the lower end of the slope 24 and moves further outwardly in contact with the edge 28 the butts are engaged by a cam in the usual fashion, whereby they are caused to ride downwardly out of engagement with the pick. As soon as the pick is released by the butts it will be returned toward its normal position by the arm 32 and then, after clearing the edge 28, will be caused to ride upwardly towards its normal central position by the action of the spring 12, riding on the lower edges of the butts of the inactive series and, after they pass, rising to its uppermost position preparatory to engagement by the butt of the leading needle of the inactive series in the reverse oscillation of the needle cylinder. Upon such engagement, the events previously described will occur on the other side of the pick, cam edges 26 and 30 then serving to define the right-hand movement of the pick.

In brief, by virtue of the slope of the under surface of each wing, the load imposed on the

leading butt due to the resulting successive action of the pick on the butts is substantially less than that which would be imposed if the pick simultaneously acted on all of the butts within its range and is less rapidly imposed with the result not only of avoiding undue stress on the leading butt but also insuring non-picking of any needle beyond the desired group due to butt deflection, i. e., lag in the swinging movement imparted by the leading butt.

In Figure 4 there is illustrated the application of the invention to a narrowing pick 58 which, as illustrated, is arranged to raise in the same operation the two leading needles of an active group. The mounting of such narrowing pick may be conventional and is such that as motion toward the left is imparted to the end of the pick, as viewed in Figure 4, it will move upwardly carrying with it the butts engaged by its wing or lateral extension, the surface of which is indicated at 60. As in the case of the widening pick, the surface 60 slopes outwardly, from the surface engageable by the side of the butt 64, in the direction, upward, in which butts are moved by the pick. Figure 4 illustrates the conditions which may arise just after the pick, having slightly raised the second butt 65, has begun the upward movement of the first leading butt 64. If the butts and cylinder walls are flexible, the leading butt 64 may be displaced to the right relative to the other butts as indicated with the result that the right-hand end of the pick may move into engagement with the side of the third butt 66. However, by this time, since initially it engaged only the second butt, it will have risen sufficiently to have its outermost portion pass above the lower edge of the third butt so that, even if it engages this butt, it engages only the side thereof and will fail to move its frictioned needle upwardly.

As in the case of the single-acting narrowing pick 58, it will be obvious that the invention is applicable to single-acting widening picks such as are also in common use.

What is claimed is:

1. The combination of a multi-needle pick and its mounting for a knitting machine which contains elongated slidable butt-carrying elements adapted to engage the pick and to be moved longitudinally thereby, the pick and mounting being arranged so that a butt moving the pick will itself be moved only after the pick has started to move at least one adjacent butt.

2. The combination of a multi-needle pick and 55 its mounting for a knitting machine which contains elongated slidable butt-carrying elements adapted to engage the pick and to be moved longitudinally thereby, the pick having surfaces respectively arranged to engage the sides and the 60 edges of butts, the surface engageable with butt edges sloping outwardly, from the surface engageable with butt sides, in the direction in which butts are moved by the pick, the pick and its mounting being arranged so that a butt moving the pick will itself be moved only after the pick has started to move at least one adjacent butt.

3. The combination of a multi-needle pick and its mounting for a knitting machine which contains elongated slidable butt-carrying elements 70 adapted to engage the pick and to be moved longitudinally thereby, the pick having surfaces respectively arranged to engage the sides and the edges of butts, said surfaces forming an acute angle with each other, the pick and its mounting being arranged so that a butt moving the pick will

itself be moved only after the pick has started to move at least one adjacent butt.

4. The combination of a multi-needle pick and its mounting for a knitting machine which contains elongated slidable butt-carrying elements adapted to engage the pick and to be moved longitudinally thereby, the pick having on opposite sides thereof butt engaging faces and overhanging wings, the faces of the wings adjacent to the butt engaging faces forming acute angles with respect to the median plane of the pick, the pick and its mounting being arranged so that a butt moving the pick will itself be moved only after the pick has started to move at least one adjacent butt.

5. In a knitting machine having elongated slidable butt-carrying elements, a pick adapted to be engaged and moved by the butts and to move the butt-carrying elements longitudinally by reason of its movement, and a mounting for the pick, the pick and mounting being arranged so that a butt moving the pick will itself be moved only after the pick has started to move at least one adjacent butt.

6. In a knitting machine having elongated slidable butt-carrying elements, a pick adapted to be engaged and moved by the butts and to move the butt-carrying elements longitudinally by reason of its movement, and a mounting for the pick, the pick having surfaces respectively arranged to engage the sides and the edges of butts, the surface engageable with butt edges sloping outwardly, from the surface engageable

with butt sides, in the direction in which butts are moved by the pick, the pick and its mounting being arranged so that a butt moving the pick will itself be moved only after the pick has started to move at least one adjacent butt.

7. In a knitting machine having elongated slidable butt-carrying elements, a pick adapted to be engaged and moved by the butts and to move the butt-carrying elements longitudinally by reason of its movement, and a mounting for the pick, the pick having surfaces respectively arranged to engage the sides and the edges of butts, said surfaces forming an acute angle with each other, the pick and its mounting being arranged so that a butt moving the pick will itself be moved only after the pick has started to move at least one adjacent butt.

8. In a knitting machine having elongated slidable butt-carrying elements, a pick adapted to be engaged and moved by the butts and to move the butt-carrying elements longitudinally by reason of its movement, and a mounting for the pick, the pick having on opposite sides thereof butt engaging faces and overhanging wings, the faces of the wings adjacent to the butt engaging faces forming acute angles with respect to the median plane of the pick, the pick and its mounting being arranged so that a butt moving the pick will itself be moved only after the pick has started to move at least one adjacent butt.
